UNITED STATES PATENT OFFICE.

HENRY W. O'NEILL, OF ELMHURST, NEW YORK, ASSIGNOR TO WESTERN ELECTRIC COMPANY, INCORPORATED, OF NEW YORK, N. Y., A CORPORATION OF NEW YORK.

SIGNALING SYSTEM.

Application filed December 17, 1924. Serial No. 756,404.

This invention relates to signaling systems and more particularly to improved methods and means for signaling over transmission lines.

Under the present telephone practice involving the use of telephone lines interconnecting different exchanges, several different methods of extending connections are employed, such as, manual to manual or manual to automatic connections. In a manual to manual connection, the subscriber in the originating exchange first secures a connection to a toll operator's position in his own exchange, who then extends the connection over a toll line to a distant exchange and rings up the toll operator as such an exchange. The toll operator at this exchange requests of the originating toll operator, the number of the desired line and then proceeds to extend the connection to the desired subscriber. In a manual to automatic connection, the toll operator in the originating exchange dials the desired line in the automatic exchange, without the aid of the toll operator at the distant exchange. Connections of these types may extend through a number of manual or automatic exchanges involving the use of several toll lines.

It is an object of this invention to provide cord circuit and toll line equipments suitable for use in extending connections of the above types.

Another object is to provide means associated with such cord circuit and toll line equipments, whereby any one of the well known types of toll lines may be employed such as, for example, ordinary wire toll lines with or without repeaters, a channel of a carrier telephone installation, a radio telephone connection, composite lines or phantom lines. That is, the nature of the signals used for performing the various functions incidental to the extension of a connection is such that the signals may be transmitted over any toll line the same distance and at the same efficiency as the ordinary voice modulated signals and without in any way curtailing the usefulness or efficiency of these various types of toll lines.

Another object of the invention is the provision of a simplified service observing arrangement whereby the service observing operator may not only ascertain the various types of connections being established over

the toll line but also observe the progress of establishing or disestablishing such connections.

Another object is the provision of a simplified signaling system involving the use of vibratory relays of the short circuiting type for production of the various signaling frequencies.

To attain these objects, according to one feature of the invention, sources of alternating current within the voice range of frequencies, using vibrating relays are employed for the signals transmitted over the toll line to accomplish the various switching and supervisory functions. A common fundamental frequency is used for the transmission of signals in either direction over the toll lines and means is provided at each end of the toll lines for automatically modulating this fundamental frequency with various alternating currents of comparatively low frequencies, transmitting the resulting signals over the line and causing the corresponding functions to be performed. In the case of the switching functions, impulses are employed which are produced by interrupting the fundamental frequency at dialing rate.

Another feature is the provision of means whereby the vibratory relays of the short circuiting type used in combination with a direct current source for the production of frequencies may be of the same type for both the fundamental alternating currents within the voice frequency range as well as for the alternating currents of low frequency and whereby repeating coils or transformers are employed for modulating the fundamental high frequencies by the low frequencies.

Another feature is the use of receiving circuits for the amplification and rectification of the variously modulated high frequency current signals to produce proper operations of relays responsive to these different types of signals received.

Another feature is a circuit arrangement whereby certain of said signals if repeated cause actions to take place to effect different supervisory indications at the cord circuit.

Another feature of the invention resides in a simple time relay arrangement in the operator's dialing equipment whereby the signaling impulse produced thereby is of such a duration that the performance of cer-

tain automatic operations in the establishing of a connection may be insured under the most adverse conditions encountered in the operation of systems of this type.

5 Another feature resides in the provision of a circuit arrangement whereby the talking conductors in the cord circuit are completed, either to the operator's telephone set should the talking key be operated or 10 to the connection beyond, between the sending of sets of dialing impulses so that both visual and audible supervisory signals may be received over the toll line during the dialing period.

15 Another feature resides in the provision of means in the cord circuit and dialing circuit equipment whereby visual supervisory signals such as busy indications may be received during the dialing period regardless 20 of whether or not dialing impulses are being sent out over the line at the moment. The arrangement is such that the line conductors are maintained looped through a repeating coil to the dialing circuit during 25 the transmission of impulses so that any incoming signal will not be interfered with as might be the case where impulses are transmitted by the opening and closing of the line conductors.

30 The nature of the invention will be more fully understood from the following description read in connection with the accompanying drawings, in which Fig. 1 shows diagrammatically a connection from 35 a subscriber's line with a toll operator's cord circuit and an associated dialing circuit arranged in accordance with this invention and located at one manual exchange. By means of this equipment, a toll operator 40 may extend connections either to another toll operator located at another manual exchange or to a subscriber reached through an automatic or machine switching exchange. Fig. 2 represents the outgoing end of a 45 special toll line equipment arranged in accordance with this invention and located at the originating exchange and by means of which voice frequency alternating current signals may be transmitted to and received 50 from the distant exchange over any type of toll line associated therewith. Fig. 3 represents the incoming end of a special toll line equipment arranged in accordance with this invention located at a distant exchange and 55 by means of which voice frequency alternating current signals of the type employed in this system may be received from or transmitted to the originating exchange. Fig. 4 represents the local equipment at this distant exchange by means of which a manual connection may be extended from the incoming toll line equipment. Fig. 5 represents a 60 portion of the equipment at this exchange and at an automatic exchange by means of 65 which automatically called subscribers may

be reached from the above mentioned toll line equipment. Only a sufficient portion of the automatic exchange has been shown to form a basis for a full explanation of the invention involved.

70 Referring now to the drawings, traffic over the system as illustrated and arranged in accordance with this invention may be outlined as follows: If it is assumed that a subscriber at 10 has established a connection 75 as far as to the toll operator's position 100 and the toll operator has inserted the answering plug 12 of the cord circuit shown at 100 into jack 11 and ascertained the number of the desired line, the toll operator will then insert calling plug 15 of the cord circuit into jack 210 of the outgoing toll line equipment 200 which is associated with a toll line 220 leading to the incoming toll line equipment 300 at the distant exchange. The 80 toll operator at 100 then proceeds in either one of two manners to extend a connection.

85 If the wanted subscriber's number can only be reached through the service of a toll operator, such as the one at position 410 at the distant exchange, she proceeds to call this toll operator in the usual manner well known in the art except that alternating currents within the voice range of frequencies on which alternating currents of low frequencies are superimposed, are used for the necessary signaling indications. That is, she causes instrumentalities in the cord circuit and the outgoing toll line equipment 200 to be operated to transmit voice frequency alternating currents of, for example, 1000 cycles modulated by an alternating current of 135 cycles over the toll line 220 to the incoming toll line equipment 300 at the distant exchange. Such signals then condition the incoming toll line equipment 300 for a manual connection and are translated by the receiving circuit equipment 350 into indications that will not only call the attention of the toll operator at position 410 105 to the fact that a connection requiring her cooperation is desired but will also serve as supervisory signals during the establishment and disestablishment of such a connection, as well as when the connection is 110 established.

115 Similar operations take place in the system if the toll operator at position 410 desires to call the toll operator at position 100 when, for example, the same type of signals are produced at the incoming toll line equipment 300, transmitted over the toll line 220 and translated by the receiving circuit equipment 250 at the outgoing toll line equipment 200 into signaling indications for the attention of the toll operator at position 100.

120 On the other hand, if the wanted subscriber's line may be reached from an automatic exchange, such as the one indicated 125

in Fig. 5, the toll operator at position 100 proceeds by operating a dialing key to connect the common dialing equipment 150 to the cord circuit and by means of instrumentalities associated with this dialing circuit, the cord circuit and the outgoing toll line equipment 200 cause voice frequency alternating currents of, for example, 1000 cycles to be transmitted to the incoming toll line equipment 300, one impulse for the preparation of this equipment for the extension of an automatic connection, and then dialing impulses which will be translated by the receiving circuit 350, to cause the automatic equipment shown in Fig. 5 to extend the connection to the wanted subscriber's line and later, voice frequency alternating currents of 1000 cycles modulated by various low frequency currents, to cause various supervisory signal indications to be given during establishment and disestablishment of the connection.

The arrangements of the toll line equipments are such that various signals for the supervision of the automatic connection are transmitted back to the operator at position 100 during the progress of the call as well as in the breaking down of the connection. Such signals may consist of the fundamental alternating currents of 1000 cycles modulated by low frequency currents of 20 cycles or 135 cycles, or signal indications consisting of the fundamental frequency modulated by low frequency current of 20 cycles transmitted in the shape of impulses at 60 per minute, these latter impulses being used when all of the toll lines are busy; or signal indications consisting of the fundamental frequency modulated by low frequency of 20 cycles transmitted in the shape of impulses at 120 per minute, which are used when the called line is busy. Such signals are all translated by the receiving circuit equipment 250 at the outgoing toll line equipment 200 into the proper supervisory signal indications for the attention of the operator at position 100.

It is to be understood that the various frequencies mentioned are simply illustrative and that the invention is not limited to the employment of these particular values but that any frequency within the voice range may be used for the fundamental alternating current, and low frequency currents of other frequencies more suitable to particular cases in the practice of the invention may also be selected.

It is believed that the arrangement shown will be more fully understood from the following detailed description of a series of calls of the types that may be completed thereby. The first type of connections to be considered will be calls extending on the so-called ring-down basis, that is, from a subscriber 10, through a toll operator's posi-

tion 100 at the originating exchange to the toll operator attending position 410 at a distant exchange and vice versa. The circuits beyond these points have not been shown as they form no part of this invention and as it is well known and understood in the art how manual connections are attended to by outgoing as well as incoming toll operators, no further explanation will be made in this respect. Assuming then, that the operator at 100 has inserted plug 12 into jack 11 and has ascertained the number of the wanted subscriber's line by the connection of her telephone set to the cord circuit, and the operation of listening key 32, she proceeds by inserting plug 15 into jack 210 after having performed the usual busy test. As a result of this action, relays 24, 23 and 201 are operated as follows: battery, winding of relay 24, winding of relay 23, sleeve contacts of plug 15 and jack 210, winding of relay 201 to ground. The operation of relays 24 and 23 closes the following circuits: one from battery, armature and front contact of relay 24, winding of relay 26, armature and back contact of relay 30 to ground, another from battery at relay 24, lamp 25, armature and front contact of relay 23, armature and back contact of relay 26 to ground at the normal contacts of listening key 32 and another from battery at relay 24, winding of relay 27 to ground at listening key 32. These latter two circuits are, however, prevented from lighting lamp 25 and operating relay 27 as relay 26 operates rather quickly so that these circuits are almost immediately broken. The operation of relay 201 closes an energizing circuit for relay 202 from battery, outer right-hand armature and front contact of relay 201, winding of relay 202 to ground. Relay 202, when operating, closes a circuit for busy signals 205 as follows: battery, right hand armature and front contact of relay 202, winding of signals 205 to ground, operating these signals to indicate to other toll operators that the toll line 220 connected with this equipment is busy.

The operator now proceeds to ring the operator at the distant exchange by actuating ringing key 34. This causes a 20 cycle alternating current source to be connected to the ring lead and ground to the tip lead of the cord circuit and the outgoing toll line equipment in which a bridged circuit containing an alternating current responsive relay 208 is located. Relay 208 responds to the 20 cycle current and closes a circuit as follows: battery, armature and front contact of relay 208, winding of relay 209 to ground. Relay 208 also, by operating this armature removes battery from the 20 cycle alternating current responsive relay 204 in the receiving circuit 250 in order that this equipment may not be disturbed by the

ringing current from the cord circuit. Relay 209 operates in the above traced circuit and closes a circuit for relay 213 as follows: battery, upper armature and front contact 5 of relay 209, winding of relay 213 to ground. Relay 213, in operating, disconnects the outgoing end of the toll line from the tip and ring leads to the jack 210 and connects it to the source of fundamental high frequency 10 alternating current on which is superimposed a low frequency current of 135 cycles. The application of this signal to the outgoing line is accomplished as follows: It should be noted that the fundamental alternating 15 current source 211 of 1000 cycles is connected to one winding of transformer 214 while a source of low frequency alternating current 212 of 135 cycles is connected through the lower armature and front contact of relay 20 209 to another winding of transformer 214 whereas a third winding of this transformer is connected to the leads now connected to the upper and inner lower armature and front contacts of relay 213. The signal is, 25 therefore, transmitted over the toll line 220 to the incoming equipment 300 received at the receiving circuit equipment 350 and is there transmitted through the input transformer 326 to the input circuit of the vacuum tube 327 serving as an amplifier. The plate circuit of the tube 327 is connected through to the grid or input circuit of vacuum tube 328, which acts as a rectifier, causing the relay 316, which in turn is connected through 30 the transformer 329 in the output circuits of the tube to operate in response to the 1000 cycle current modulated by the 135 cycle current. That is, relay 316 and the circuit therefor are tuned to respond to this type of signals only in a manner well known in the art. As this relay attracts its armature an obvious circuit is closed for relay 217 which in operating closes a circuit to ground for lead 330 to cause the operation of relay 401 as follows: battery, make-before-break contact of relay 408, left-hand winding of relay 401, lead 330, lower armature and back contact of relay 319, outer right hand armature and back contact of relay 307, left hand armature and front contact of relay 317 to ground. The operation of relay 401 closes a circuit for the busy signals 426 at the jacks 425, 430 and 429 of the toll line as follows: battery, at relay 408, left hand armature and front contact of relay 401, busy signals 426 to ground, thus making the switchboard end of the toll line at this exchange busy for calls originating thereat. Relay 401 also closes a locking circuit for 45 itself from battery at the armature and back contacts of relay 402 through its right hand armature, front contact and winding to ground. Relay 401 closes a circuit for the outward line lamp 427 as follows: battery, armature and back contact of relay 402,

right-hand armature and front contact of relay 401, left hand armature and back contact of relay 404, right-hand armature and back contact of relay 411, lamp 427 to ground, causing this lamp to be lighted to 70 indicate to the operator at 410 that her attention is desired on this line.

In answer to this signal, the operator at 410 inserts her plug 428 into jack 425, causing relay 402 to operate over the following 75 circuit: battery, sleeve contacts of plug 428 and jack 425, right hand winding of relay 402, lead 431, inner right hand armature and back contact of relay 307 to ground. The operation of this relay opens the locking circuit for relay 401 which is presently released on the subsequent operation of relay 408 causing the supervisory signal 427 to be extinguished. That is, relay 408 is operated by the closing of an obvious energizing circuit 80 at the armature and front contact of relay 402. The operation of this relay thus in addition to opening the original energizing circuit for relay 401 also closes a circuit for maintaining the busy signals 426 operated over the following circuit: battery, armature and front contact of relay 408, busy signals 426 to ground. The operation of relay 402 also applies battery to the lead 432 which causes the operation of relay 319 as follows: 85 battery, armature and front contact of relay 402, lead 432, winding of relay 319 to ground. The operation of relay 319 closes the tip and ring leads of the toll line to the tip and ring of jack 425 at its upper armatures and front contacts and disconnects the toll line from the leads to the automatic equipment at the back contacts of these armatures. The operation of relay 319 also opens the circuit for relay 401 which, as hereinbefore 90 stated, is already released and completes a connection to relay 320 for supervisory purposes as will hereinafter be described.

The operator at 410 now actuates her listening key connecting her telephone set in 110 the usual manner to the cord circuit and receives the details of the call from the operator at 100 who has also by this time actuated her listening key 32 and connected her telephone set to her cord circuit. The operator at 410 then proceeds to extend the connection to the wanted subscriber's line and call the subscriber and the connection with the calling subscriber is also attended by the operator at 100, in accordance with the well 115 established practice in the art of telephony. Conversation between the subscriber at 10 and the called subscriber may then take place.

In case the call extended to the operator 125 at 410 is intended for a subscriber that may be reached through the assistance of an operator at another distant exchange, that is, if the operator at 410 is merely employed as a connecting operator for a so-called through 130

connection, it may be necessary to send supervisory signals from the operator at 100 at the originating exchange over the toll line 220 through the incoming toll line equipment 300 to the cord circuit of the operator at 410 and this may be done by the operation of the ringing key 34 whenever such supervisory signaling is desired. The function of the circuit in this instance is the same as 10 that already described when the key was first operated, except that when relay 317 is now operated in response to a signal, over the toll line 220, of 1000 cycle alternating current modulated by a 135 cycle current, 15 the ground at the left hand armature and front contact of this relay operates relay 320 as follows: battery, winding of relay 320, lower armature and front contact of relay 319, outer right hand armature and back 20 contact of relay 307, left hand armature and front contact of relay 317 to ground, causing the operation of relay 320. This causes the disconnection of the tip and ring leads of the toll line 220 and connects current from 25 the 20 cycle alternating current source 331 and ground to the tip and ring leads of the switchboard end of the incoming toll line equipment through the jack 425 to the cord circuit of the operator at 410, causing supervisory signal indications to be displayed in 30 the cord circuit at 410 and the connection may be extended further as is well known in the art.

In case the incoming operator at 410 at 35 the distant exchange decides to extend a connection to a subscriber that may be attended to by the operator at 100, i. e. a connection in the opposite direction on the toll line 220, a procedure similar to that described above 40 is followed. The operator at 410 after inserting her plug 428 into jack 429 causing operations to take place resulting in the operation of relay 319, actuates her ringing key (not shown) in the same manner as the operator at 100 operated her ringing key 34. Twenty-cycle alternating current and ground is thereby connected to the tip and ring leads of the toll line equipment 300, causing relay 332 bridged across the line to 45 operate. The operation of this relay closes a circuit for relay 310 as follows: battery, right hand armature and front contact of relay 332, winding of relay 310 to ground. This relay, after having disconnected the 50 portions of the tip and ring leads connected to jack 428, connects at its upper and inner lower armatures and front contacts, leads connected through one winding of a repeating coil 336, another winding of this coil is connected to an alternating current source 334 having a frequency of 1000 cycles, while a third winding is connected to an alternating current source 335 having a frequency of 135 cycles and that is now connected through 55 the inner left hand armature and front con- tact of relay 332. Thus, an impulse from the 1000 cycle source modulated by current from the 135 cycle source is effective through the tip and ring leads of toll line 220, and transmitted at the outgoing toll line equipment 200 through the upper and inner lower armatures and back contacts of relay 213 and at the receiving circuit 250 through the input transformer 230 to the input circuit of the vacuum tube 231. This receiving circuit is similar to the receiving circuit 350, that is, the plate circuit of the amplifier tube 231 is connected to the grid or input circuit of a second tube 232, which acts as a rectifier causing relay 221 which is in turn connected 60 through the transformer 235 in the output circuit of the tube, to operate in response to the 1000 cycle current modulated by the 135 cycle current. The operation of relay 221 closes a circuit for relay 222 as follows: 65 battery, left hand winding of relay 222, inner right-hand armature and back contact of relay 201, armature and contact of relay 221 to ground. Relay 222, in operating, closes at its left-hand armature and front contact, 70 a circuit for the busy signals 205 as follows: battery, left-hand armature and front contact of relay 222, signals 205 to ground, making this end of the toll line busy. The operation of relay 222 also closes a locking circuit for itself from battery at the make-before-break contact of relay 201, right-hand armature, front contact and winding of relay 75 222 to ground. A circuit is also closed for the "inward" line signal 226 as follows: bat- 80 ttery, armature and make-before-break contact of relay 201, right-hand armature and front contact of relay 222, right-hand armature and back contact of relay 227, lamp 226 to ground, causing the illumination of this 85 lamp as an indication to the operator at 100 that the connection is desired on this line.

In answering this signal, the operator at 100 inserts plug 15 into jack 228 and relays 24, 23 and 201 are operated in a circuit as 90 hereinbefore traced. The operation of relays 24 and 23 in the cord circuit have also the same effect as hereinbefore described, i. e., that lamp 25 is not illuminated but the operation of relay 201 by opening its make- 95 before-break contacts to battery, causes the signal 226 to be extinguished. The operation of relay 201 also causes the release of relay 222 and the operation of relay 202 which thus maintains busy signals 205 oper- 100 ated over an obvious circuit. The operator at 100 now actuates her listening key 32, connecting her telephone set to the cord cir- 105 circuit and receives the details of the call from the operator at 410 who has already by this 110 time actuated her listening key correspond- 115 ing to 32 and connected her telephone set 39 to her cord circuit. The operator at 100 then proceeds to extend the connection to 120 the wanted subscriber's line and calls the 125 130

subscriber in accordance with the well established practice in the art of telephony whereupon conversation between the subscriber at the distant exchange and the subscriber at 10 may take place.

In case the call extended to the operator at 100 is intended for a subscriber that may be reached through another exchange in this direction, i. e., if the operator at 100 is merely employed as a connecting operator for a through connection, it may be necessary to send supervisory signals from the operator at 410 at the distant exchange over the toll line 220 through the outgoing toll line equipment 200 to the cord circuit of the operator at 100. This may be done by the operator at 410 actuating her listening key whenever such supervisory signaling is desired. The function of the circuits in this instance is the same as that already described when the ringing key was first operated except that when relay 221 was operated, instead of operating relay 222, a circuit is completed for relay 223 as relay 201 is now operated. This circuit may be traced as follows: battery, winding of relay 223, inner right-hand armature and front contact of relay 201, armature and contact of relay 221 to ground. The operation of relay 223 connects current from a 20 cycle alternating current source 224 and ground at its armatures and front contacts to the tip and ring leads and contacts of the jack 210 and plug 15 to cause the operation of relay 30 in the cord circuit at 100. The operation of relay 30 causes the release of relay 26 and the circuits for lamp 25 and relay 27 through the armature and back contact of relay 26, are now completed, causing relay 27 to back up and lamp 25 to be lighted to indicate to the operator at 100 that her attention is desired.

These various connections may be released when the conversation ceases by merely re-moving the plugs and the various relays will return to normal position as is well known in the manual telephone art.

The second type of connections to be considered are calls extended on the so-called automatic basis, i. e., from the subscriber at 10 through the toll operator's position at 100 at the originating exchange, over the same toll line 220 to the incoming toll line equipment 300 which will, in this instance, be prepared to extend the call through an automatic equipment such as is shown in Fig. 5 and through the associated switches to a subscriber such as 510. As the automatic exchange equipment does not form any part of this invention, only a small portion has been shown sufficient to illustrate how it is effected by and how it reacts upon the toll line equipment in accordance with this invention. In fact, any well known type of automatic equipment may be used as long

as the proper signal indications may be sent or received to perform the proper functions with respect to dialing and signaling supervisory indications through the toll line equipment.

Assuming then, as hereinbefore, in connection with calls extended on the ring-down basis that the toll operator at 100 has inserted the plug 15 into jack 210 and relays 201 and 202, signals 205, relays 23, 24 and 26 have all been operated and that the supervisory lamp 25 is not lighted, due to the combination of the slow releasing and slow operating relays 26 and 27 as hereinbefore described, the toll operator at 100 will, in this instance, instead of operating ringing key 34, operate the dialing key 35. The operation of this key establishes the following circuit for the operation of relay 37 as follows: battery, winding of relay 37, lower contacts of dialing key 35 to ground at the outer left-hand make-before-break contacts of relay 38. Relay 37 in operating disconnects the tip and ring leads of the cord circuit from the plug 15 and connects thereto leads 40 and 41, the other ends of which are connected through right-hand windings of transformer 42. Another circuit is completed for the operation of relay 43 as follows: battery, winding of relay 43, inner left-hand contact of relay 38, upper contacts of dialing key 35 to ground. Relay 43, in operating, closes a circuit for relay 38 as follows: battery, winding of relay 38, right-hand armature and front contact of relay 43 to ground at the upper contacts of dialing key 35, causing this relay to operate. It should be noted that when the dialing key was operated, a circuit for the upper left-hand winding of transformer 42 was closed as follows: from battery at the alternating current source 44, upper left-hand winding of transformer 42, contacts 48 of dial 46, upper contacts of dialing key 35 to ground. As this source 44 includes a vibrator operating at, for example, 1000 interruptions per second, a 1000 cycle alternating current is induced in the upper left-hand winding of transformer 42 and transmitted to the tip and ring contacts of plug 15 to the toll line 220. This impulse of high frequency alternating current is, however, discontinued the moment relay 43 is released which takes place as soon as relay 38 is operated. Relay 43 is released by the opening of the inner left-hand make-before-break contacts of relay 38, whereas relay 38, in operating, provides a locking circuit for itself through its inner left-hand armature and front contact to the ground at the upper contacts of dialing key 35. On the operation therefore, of relay 38 and release of relay 43 a circuit is completed from the alternating current source 44, through the lower left hand winding of transformer 42, the right armature

and front contact of relay 38, right hand armature and back contact of relay 43 to ground at the upper contacts of key 35. Alternating current from source 44 is therefore now passing through the two left-hand windings of the transformer 42 in opposite direction and consequently no induced current is effective through the secondary windings of the transformer under this condition. The cycle of operation of these relays therefore provides that the impulse produced in this manner is of a sufficient duration to insure that the required operations will taken place under all circumstances even though the functioning of the individual devices and circuits may not be entirely up to the standard, that is, the operation hereinafter described will have sufficient time to be performed. It should be pointed out that the length of this impulse is always the same and is produced by this simple cycle of operations of the above mentioned two relays 43 and 38 only without the use of any involved timing relay combinations. This high frequency alternating current impulse at a frequency of 1000 cycles is now received at the incoming toll line equipment 300 through transformer 326 bridged across the tip and ring leads. After having been transmitted through the amplifying tube 327 and rectifying tube 328, this impulse causes the operation of relay 301, which responds to a rectified current from an alternating current at this frequency only.

The operation of relay 301 closes a circuit for relay 302 as follows: battery, right hand armature and back contact of relay 317, winding of relay 302, outer left hand armature and back contact of relay 306, armature, front contact of relay 301 to ground at outer left hand armature and back contact of relay 332, causing the operation of this relay. Relay 302 in turn closes a circuit for busy signals 426, from battery right-hand armature and front contact of relay 302, lead 436, signals 426 to ground, making the manual end of this trunk circuit busy. The operation of relay 302 also opens a circuit normally extending through the right hand winding of polarized relay 303 which may be traced as follows: battery, left hand armature and back contact of relay 302, armature and back contact of polarized relay 303, right hand winding of relay 303 to ground. This circuit normally holds relay 303 in the non-operated position shown, as the current through a circuit closed for the left hand winding of relay 303 from battery, armature and back contact of relay 305, winding of relay 304, left hand winding of relay 303 to ground normally opposes this current through the right hand winding of this relay and relay 303 is therefore now permitted to operate. The operation of relay 303 applies, at its armature and front con-

tact as soon as the impulse from the dialing circuit ceases and relays 301 and 302 release, a short circuit for relay 304 which, it should be noted, is normally operated, i. e. the current from the left hand armature and back contact of relay 302 now passes through the armature and front contact of relay 303 to the left hand winding of relay 303 to ground. Relay 304, therefore, in releasing, closes a circuit for relay 305, as follows: battery, make-before-break contacts of relay 408, left hand armature and back contact of relay 401, lead 433, armature and back contact of relay 304, winding of relay 305, left hand winding of relay 303 to ground. The operation of relay 305 closes a circuit for relays 306 and 307 as follows: battery, armature and front contact of relay 305, windings of relays 306 and 307 in series to ground. The operation of relay 307 by closing its left hand armature to the corresponding front contact retains the busy signal 426 operated after relay 302 is released through a circuit as follows: battery, left hand armature and front contact of relay 307, lead 436 to ground at the busy signal 426. The operation of relay 307 also includes a resistance to battery in the lead 431 by removing the ground at its inner right hand armature and back contact as follows: battery, armature and front contact of relay 305, resistance 335 and lead 431 to make the sleeve leads of jacks 425 and 429 busy. The ground at the inner right hand armature of relay 307 is now applied at the front contact therefor to a conductor 550 leading to the automatic equipment shown in Fig. 5. The result of the high frequency alternating current impulse sent from dialing equipment 150 is therefore that a ground is applied on lead 550 to prepare the automatic equipment for the reception of directive and supervisory impulses and when this equipment is seized as hereinafter described a signal is returned therefrom and the dialing may begin.

The effect of this ground on lead 550 is as follows: Relay 511 is operated over the following circuit: battery, winding of relay 511 to ground at lead 550. The operation of relay 511 closes a circuit as follows: battery, relay 512, inner right hand armature and contact of relay 514, armature and back contact of relay 522, left hand armature and front contact of relay 511 to ground. This causes the operation of relay 512 which in turn closes an obvious circuit for rotary magnet 518 of the finder switch F. The rotary magnet 518 in operating, causes the line switch F to start hunting for an idle district switch in a manner well known in the art.

With an idle district switch, such as is diagrammatically illustrated at G and the

idle condition which is designated by the presence of battery on the test terminal 520, relay 522 is operated in a circuit extending from battery, sequence switch contact 540, 5 armature and back contact of relay 525, terminal 520 and wiper 521, right hand armature and front contact of relay 511, left and right windings of relay 522 in series to ground. Relay 522, in operating, closes a 10 short-circuit around its right hand high resistance winding at its armature and front contact to the ground at the left hand armature and front contact of relay 511. The operation of relay 522 opens the circuit 15 at its armature and back contact for relay 512 which in turn opens the circuit for rotary magnet 518, whereupon this magnet releases and stops the switch F at this position. The operation of relay 522 also closes a 20 circuit for relay 514 as follows: battery, winding of relay 514, armature and inner front contact of relay 522 to ground at the left hand armature and front contact of relay 511. Relay 514, in operating, closes a locking 25 circuit for itself through its inner left hand armature and inner front contact to the ground on lead 550. Relay 514, at its two outer left hand armatures and front contacts closes the tip and ring leads from the 30 brushes 598 and 545 of the switch F to relay 527 and lead 552 for purposes hereinafter to be set forth. Relay 514 at its left hand inner armature and one front contact closes a circuit for relay 525 as follows: battery, 35 winding of relay 525, brush 541 of switch F, left hand inner armature and said front contact of relay 514 to ground on lead 550, causing the operation of relay 525. Relay 525, in attracting its armature, removes 40 battery from the test terminal 520 of switch F, whereupon relay 522 releases, and as relay 514 is held operated, the ground from the left hand armature and front contact of relay 511 through the armature and back 45 contact of relay 522 has no effect on relay 512 or magnet 518.

The operation of relay 525 of the selected 50 district switch causes an idle sender to be selected in a well known manner, and when relay 500 operates from the ground at relay 332 over lead 552, relay 501 is also operated through intermediate relays (not shown) to cause a dialing signal to be given to the operator at 100 in the following manner. Relay 501, in operating, places a ground on the tip conductor of the switch F. This ground causes relay 527 to operate in a circuit extending from battery, outer right hand armature and back contact of relay 528, winding 55 of relay 527, left hand outer armature and front contact of relay 514, brush 598, sequence switch spring 580 to ground at the armature and front contact of relay 501. Relay 527, in operating, causes the ground 60 on lead 550 to be connected to conductor 557

through its armature and front contact, which ground causes the operation of relay 309 over a circuit as follows: battery, winding of relay 309, conductor 557, armature and front contact of relay 527 to ground on conductor 550. The operation of relay 309 closes a circuit for relay 310 as follows: battery, right hand armature and front contact of relay 309, armature and normally closed contact of polarized relay 311, right hand armature and back contact of relay 330, winding of relay 310 to ground. Relay 310, in operating, closes a circuit through its upper and inner lower armatures and front contacts from the left hand winding of transformer 313 to the incoming tip and ring leads of toll line 220, thus transmitting an impulse from the 1000 cycle alternating current source 334 modulated by current from the 20 cycle source 331 by means of the upper right hand winding of transformer 336. This impulse, however, is of short duration as the operation of relay 310 closes at its outer lower armature and front contact a circuit to ground at right hand armature and back contact of relay 404 for the left hand coil of relay 311 from battery at the right hand armature and front contact of relay 309, causing relay 311 to operate its armature in the opposite direction and thus opening the energizing circuit for relay 310 which is thereby released and causes the impulse to cease. This modulated signal causes the lamp 25 to become illuminated to indicate to the operator at 100 that dialing 100 may begin. The impulse is received at the receiving circuit equipment 250 over the following circuit: from the left hand winding of transformer 313 through the tip and ring conductors of the toll line 220 to the incoming winding of transformer 203 and is effective through the receiving equipment 250 in the manner hereinbefore described for other signals to cause the operation of relay 204. The operation of relay 204 opens the 105 closed circuit from battery at the left hand armature and front contact of relay 201 through the left hand winding of polarized relay 203 to ground, causing this relay to operate as the current through the closed circuit through the right hand winding of relay 205 normally opposes the current in the left hand winding. This latter circuit may be traced as follows: from battery, left hand armature and front contact of relay 201, left 110 hand armature and back contact of relay 207, winding of relay 206, right hand winding of relay 203 to ground. In operating, this relay provides a locking circuit for itself through its right hand winding, armature and front contact to battery at the left hand armature and front contact of relay 201 as soon as relay 204 is released when the 115 impulse from the incoming toll line equipment 300 ceases. The last mentioned circuit 120

short circuits relay 206 which is thereby de-energized. A circuit is now closed for relay 207 as follows: battery at relay 201, armature and back contact of relay 206, winding of relay 207, left hand winding of relay 203 to ground. The operation of relay 207 opens a shunt circuit through its right hand armature and back contact, for the left hand high resistance winding of relay 201, thus increasing the resistance for the sleeve circuit sufficiently to cause relay 23 to release and close a circuit for lamp 25 at its armature and back contact to ground from battery at relay 24. This signal, now indicates to the operator that dialing operations may begin.

Current from the 1000 cycle source 44 at the dialing circuit 150 is now in position to be connected to the receiving circuit 350 as a pulsing current. When, therefore, the operator at 100 operates the dial 46 in accordance with the number of the desired line, ground is connected to the winding of relay 37 from the off-normal contacts 47 of the dial, causing relay 37 to operate over an obvious circuit. The operation of this relay closes a circuit from the leads 40 and 41 of the toll line 220 to the upper and lower right hand windings of transformer 42 the left hand windings of which are closed from the source 44 to the ground at the upper contacts of dialing key 35, the lower winding through the right hand armature and front contact of relay 38, which is operated at this time, and then through the right hand armature and back contact of relay 43 and the upper winding through the pulsing contacts 48 of dial 46. Impulses of 1000 cycle current from this source are therefore now ready to be transmitted to the receiving equipment 350 at 300. The pulsing contacts 48 of the dial are operated during the return of the dial to normal in accordance with the desired number and thereby cause an interruption of the circuit through the upper left hand winding of transformer 42 to the source 44 and in this manner pulses of 1000 cycle current are transmitted to the distant end, each pulse being equal in time to the open period of the pulsing contacts 48 of the dial. When, therefore, the 1000 cycle pulses are received over the line from the outgoing end, they are transmitted through the receiving equipment 350 as hereinbefore described to cause relay 301 to operate and release at a rate corresponding to the rate of interruptions of the pulsing contacts 48. Relay 301 thus disconnects at its armature and back contact the ground at relay 332 from lead 552 to cause selecting operations to be performed by the automatic exchange equipment shown in Fig. 5. That is, relay 500 is caused to respond to the impulses over a circuit as follows: battery, winding of pulsing relay 500, sequence switch 581, wiper 545 of switch F, middle upper armature and front contact of

relay 514, inner upper armature and back contact of relay 528, lead 552, armature and back contact of relay 301 to ground at the outer upper armature and back contact of relay 332.

To turn now to the operation of the automatic equipment when all the pulses are registered in the sender, ground is removed from the tip lead at relay 501, thereby causing relay 527 to release which in turn opens the circuit to ground over lead 551 for relay 309. Relay 309, in releasing, closes a circuit for relay 310 as follows: battery, right hand armature and back contact of relay 309, armature and left hand contact of relay 311, right hand armature and back contact of relay 330, winding of relay 310 to ground. The operation of relay 310 as hereinbefore described, causes the transmission of an impulse of 1000 cycle current modulated by a 20 cycle current over the toll line 220 through the receiving equipment 250 and causes the lamp 25 to be extinguished as an indication that the subscriber's number has been registered on the sender. It should be noted that in this case, on the operation of relay 204 in the receiving equipment 250, relay 205 is permitted to release. When this impulse ceases and relay 204 is restored to normal, a shunt circuit is established at its armature and back contact for relay 207, causing this relay to release, thereby reestablishing the shunt circuit for the left hand winding of relay 201 so as to again cause the marginal relay 23 to operate and open the circuit for signal 25 at its armature and back contact.

When the wanted subscriber's line at 510 is reached, a ground is connected at the contact 529 from sequence switch contact 582 to wiper 538 of the switch F, whereupon relay 528 is operated in a circuit which may be traced from battery, winding of relay 528, make-before-break contacts of relay 528, outer right hand armature and back contact of relay 514, brush 538 to the ground at contacts 582. At its inner right hand armature and front contact, relay 528 establishes a locking circuit for itself to the ground on conductor 550. At its outer right hand armature and back contact this relay opens the energizing circuit for relay 527 and at its inner left hand armature and back contact, relay 528 opens the dialing conductor 552 for pulsing relay 500. At its outer left hand armature and front contact, relay 528 establishes a circuit from ground at conductor 550 to the conductor 553, thus closing a circuit for relay 318 as follows: battery, winding of relay 318, make-before-break contacts of relay 318, conductor 553, outer left hand armature and front contact of relay 528 to ground on conductor 550. Relay 318, in operating, closes a locking circuit for itself through its left hand armature and front

contact directly to ground at conductor 550 and at its right hand armatures and front contacts extends the tip and ring leads from the toll line equipment 300 to the tip and ring leads connected at brushes 598 and 545 of the switch F.

If the wanted subscriber's line is idle, the ground connected at contact 529 is now completed at the middle upper armature and 10 front contact of relay 528 to conductor 551 causing the operation of relay 309 which through operations as hereinbefore described causes an impulse from the 1000 cycle source modulated by 20 cycle current to be transmitted to the toll line 220 through the receiving equipment 250 and causes the sequence of operations of relays 204, 203, 206 and 207 as hereinbefore described to light the lamp to indicate to the operator at 100 20 that the called subscriber is idle and that ringing operations may begin.

When, therefore, all the digits corresponding to the number of the desired line have been dialed, the operator at 100 may 25 restore the dialing key 35 and thereby release relay 39 and disconnect the dialing circuit 150 from the operator's cord circuit.

As the operator at 100 is now connected to the wanted subscriber's line she may signal the subscriber by the operation of key 34 and circuits are established in the same manner as described with calls established on a ring-down basis, i. e., an impulse from the 1000 cycle source 211 modulated by current 30 from the 135 cycle source 214 is transmitted from the outgoing toll line equipment 200 over the toll line 220 to the receiving equipment 350, causing the operation of relay 316 and through the contacts and armature of 35 this relay, relay 317 is operated over the following circuit: battery, winding of relay 317, contact and armature of relay 316, armature and back contact of relay 315, outer left hand armature and back contact of relay 40 332 to ground. The operation of relay 317 closes a circuit to ground for conductor 554 causing the operation of relay 599 over the following circuit: battery, winding of relay 599, sequence switch 594, brush 597 of switch 45 F over lead 554, outer right hand armature and front contact of relay 307, to the ground at the left hand armature and front contact of relay 317. The operation of relay 599 causes the application of ringing current 50 from source 592 over the established connection to actuate the wanted subscriber's bell. 55

When the called subscriber answers in response to this ringing signal by removing his receiver from the switchhook, ground is removed from contact 582 at switch F thereby 60 opening the circuit for relay 309 and the release of this relay causes a signal from the 1000 cycle source 334, modulated by current from the 20 cycle source 331, to be transmitted 65 to the cord circuit at 100 to cause lamp

25 to be extinguished by a series of operations as hereinbefore described, to indicate to the operator that the subscriber has answered. Conversation may now begin between the subscriber at 10 and the subscriber 70 at 510 as the operator at 100 will, as is well known in the art, establish a connection through plug 12 and jack 11.

At the termination of the conversation, the subscriber at 510 upon replacing the receiver 75 on the switchhook again causes ground to be placed at contact 529 of switch F from contact 582 thereby operating relay 309 and an impulse of 1000 cycle current modulated by current from the 20 cycle source to be thereby transmitted as hereinbefore described to light lamp 25 as a disconnect signal. The operator at 100 now proceeds to take down the connection by withdrawing plug 15 80 from jack 210. As a result of this action, relays 24, 23 and 201 are immediately released. The release of relay 24 causes the release of relay 26 and the extinguishing of lamp 25. The release of relay 201 causes a signal from the 1000 cycle source modulated by current from a 20 cycle source to be transmitted to the incoming toll line equipment 300 as follows: When relay 201 releases, and before relay 202 has time to release, a circuit is closed from battery at the make-before-break contacts of relay 201 through the left hand armature and front contact of relay 202 through the winding of relay 213 to ground. The operation of relay 213, 95 which is slow to release, closes the toll line 220 to the upper winding of transformer 214 and an impulse from the 1000 cycle source at 211 modulated by current from the 20 cycle source 224 is transmitted to the receiving equipment 350. This causes the operation in 100 this equipment of relay 301, in the manner as hereinbefore described by the 1000 cycle current and the operation of relay 322 through transformer 311 and these relays in operating close a circuit for relay 302 as follows: 105 battery, right hand armature and back contact of relay 317, winding of relay 302, armature and front contact of relay 315, outer left hand armature and front contact of relay 306, armature and front contact of relay 301 to ground at the outer left hand armature and back contact of relay 332. The operation of relay 302 removes battery from 110 the left hand winding of relay 303, permitting this relay to release and cause the operation of relay 304 and consequently the release of relay 305 which breaks the energizing circuit for relays 306 and 307. Relay 307 in releasing disconnects ground from 115 lead 550 which thereby effects the release of relay 318 and the automatic switching equipment as it will be noted that relays 511, 514 and 528 are respectively locked from this ground. The release of relay 307 also releases the busy signals 426 at the manual end 120

125 130

of the toll line at this exchange and removes in conjunction with relay 305 the busy potential on the sleeves of jacks 425 and 429.

If, in the course of completion of the connection by the automatic exchange equipment the trunks through the switches 508, 509 and 511 for extending the connection are found busy, intermittent ground is connected to the terminal 529 from an interrupter, such as 583, or any other suitable means at a certain rate, for example, 60 interruptions per minute. The first impulse to ground will operate relay 528 and the following interruptions will release and operate relay 309, at a corresponding rate to alternately close and open the circuit for relay 310 through the operations of relay 311 as hereinbefore described. This causes impulses from the 1000 cycle source modulated by current from the 20 cycle source to be sent at the rate of 60 per second. These impulses will therefore intermittently light lamp 25 at this rate in a manner which is now believed to be obvious. The flashing of lamp 25 indicates to the operator that all trunks are busy.

In the same manner, if the called subscriber is found busy, ground will be connected to terminal 529 at a different rate, such as will produce for example 120 impulses per minute from an interrupter such as 584 and the flashing of the lamp 25 at this rate will indicate to the operator that the wanted subscriber's line is busy. As is well known in the art, both trunk busy and subscriber's line busy signals may arrive over the line while the dialing is taking place. In accordance with this invention such busy signals may be effective in the cord circuit during dialing; that is, for example, in case a busy signal should arrive at the cord circuit while the talking key is operated not only will the lamp 25 indicate this condition but also as soon as relay 37 is released after a set of impulses representing one digit is completed and the talking conductors extended to the subscriber's telephone circuit, this busy condition will be audibly indicated at the operator's receiver. The different types of busy signals will, of course, in this case be identified by the operator by the rate at which the signals are interrupted. On the other hand, in case a set of impulses representing a single digit are in process of being transmitted the fact that the talking conductors are not interrupted but maintained as a closed loop through repeating coil, the busy signals will be received without interference through the receiving circuit 250 and operate the lamp 25 accordingly. Therefore, regardless of whether or not dialing is taking place, a busy signal will be indicated at the operator's cord circuit in one form or another or both visually and audibly. This may be of particular importance when numbers containing a large num-

ber of digits are in process of being transmitted as in such cases the operator's time will be saved and a call abandoned at the first indication of a busy condition of the path selected.

It should also be noted that lamp 25 may be flashed by the called subscriber at the rate at which the switchhook is moved up and down. Relay 309 will then be operated when the switchhook is down and release when the switchhook is up.

If the operator at 100 desired to rering the called subscriber after he has replaced his receiver on the switchhook, she operates the ringing key 34 and the circuits function in exactly the same manner as when the wanted subscriber was first called, i. e., impulses from the 1000 cycle source modulated by current from the 135 cycle source causing the operation of relay 317 which in turn causes the operation of relay 599 which applies ringing current from source 592 through the established connection to rering the wanted subscriber.

It now only remains to consider one more type of connections that may be extended by the use of this toll line equipment, namely, a call intended for what is commonly known as the "out delayed" or "repeater" operator, i. e. an operator having equipment arranged similarly to the operator at 410 only that this operator is reached by having the operator at 100 dial a certain toll or special code number. In this case, the operator at 100 proceeds in the same manner as when dialing for an automatic subscriber such as the one located at 510, only instead of reaching this subscriber's line terminals she will be connected to terminals such as 610 connected directly to ground and battery. This battery and ground are transmitted back over the line and will cause the operation of relay 516. Relay 516, in operating, causes ground to be connected to lead 557 resulting in the operation of relays 404 and 401. The operation of these relays causes the lighting of signal lamp 405 as well as the operation of the busy signals 426. Relays 404 and 409 in operating provide locking circuits for themselves to the battery at relay 402 and the operation of relay 404 provides a circuit from this battery for signal 405, which in lighting calls the "out-delayed" operator's attention to this trunk line. Relay 401 closes a circuit for the busy signal 426 as shown. The operation of relay 404 also removes the ground from the conductor 439 and applies this ground on conductor 434 while the operation of relay 401 interrupts the battery normally connected to lead 433 to effect the release of the automatic equipment; that is, the removal of battery from lead 433 causes relays 305, 306 and 307 to release and the ground for lead 550 to be removed, whereas the application of ground at lead 434 oper-

ates the relays 309 and 310 to send a signal as hereinbefore described and light lamp 25 at the operator's position at 100 to indicate that the lamp 405 at the "out-delayed" 5 operator's position has been lighted. The removal of ground from the lead 439 serves the purpose of preventing relay 331 from operating and release relay 310 until this "out-delayed" operator answers the call as 10 will hereinafter be described.

In answering this call the plug of this operator's cord circuit (not shown) will be inserted in the jack 430. Relays 407 and 402 will now be operated over an obvious circuit through the sleeve contacts of the "out-delayed" operator's plug and jack 430. The operation of relay 407 will disconnect the jacks 425 and 429 from the toll line and provide a ground at its outer lower armature and front contact for maintaining relay 309 operated for the time being. Relay 402 on the other hand breaks at its armature and back contact locking circuits for relays 401 and 404 and closes at this armature and 25 front contact obvious energizing circuits for relays 408 and 319. The operation of relay 319 connects the toll line conductors to the jack 430 while relay 408, by operating its armature, prevents battery from being 30 connected to the lead 433 and connects this battery to the circuit for signals 426 to maintain these signals operated after relay 401 is released. Relay 404 in releasing opens the ground connection for relay 409 and 35 establishes the ground for relay 311 which will now operate as it will be remembered that relay 309 is maintained energized by ground at relay 407 and relay 310 will therefore release upon the operation of relay 311 40 and cause the signal lamp 25 at the operator's position at 100 to be extinguished to indicate that the "out-delayed" operator is ready to communicate with this operator.

When the "out-delayed" operator disconnects by removing her plug from jack 430, relays 407, 402 and 408 are released and all circuits are restored to normal condition, relay 309 naturally being also released causes the signals to be transmitted as hereinbefore 50 described to light lamp 25 as disconnect signal for the operator at 100.

It should be noted that in the event of the "out-delayed" operator is used in a through connection, the operator at 100 may send supervisory signals to this operator's cord circuit by virtue of the operation of relay 317 and in case the "out-delayed" operator desires to call the operator at 100 she may do so by moving the plug in and out of jack 430. 60

There is another phase of this invention, namely a service observing circuit arrangement the principal parts of which are shown at 380 and the operation of which will now be described. It should be noted that in the case 65 of a ring-down connection when relay 401

operates to light signal 427, the service observing signal 321 is also lighted over a circuit as follows: battery, relay 402, right-hand armature and front contact of relay 401, conductor 438, inner left hand armature 70 and back contact of relay 306, signal 321 to ground. The service observing busy signal 322 also operates at this time over a circuit from battery at relay 408; left-hand armature and front contact of relay 401, conductor 75 436, signal 322 to ground. These signals thus indicate that the toll line 220 has been appropriated for a connection to be established on a ring-down basis. The service observing operator may now connect her telephone set (not shown) by means of plug 381 and jack 324 to toll line 220 through the contacts and armatures of relay 323. When relay 401 is released at the time the call is answered by the toll operator at 410, the service observing lamp 321 is extinguished while the busy signal 322 is maintained operated with busy signals 426 through the operation of relays 402 and 408 until the connection is released. These operations in the service observing equipment 380 therefore indicate the progress of a call on the ring-down basis.

On the other hand, in case a connection is extended on the automatic basis, the service observing equipment 380 operates in a different manner to indicate the progress of an automatic call. It should be noted that when relays 302 and 306 and other relays associated therewith operate when a preliminary impulse of alternating current of 1000 cycles is sent out from the dialing equipment 150 to prepare the automatic equipment for the reception of directive impulses, these relays close a circuit for the service observing signal 322 as follows: battery, right hand armature and front contact of relay 302, busy signal 322 to ground and another circuit for signal 321 as follows: battery, right hand winding of transformer 340, left hand armature and back contact of relay 309, inner left hand armature and front contact of relay 306, lamp 321 to ground. It should be noted that the left hand winding of transformer 340 is connected to the 20 cycle source 331 and consequently the circuit for signal 321 is effected by an induced current from the transformer in such a manner that a corresponding so-called "quiver" effect will be perceptible in the illumination of the lamp. This distinctive effect is taken by the service observing operator as an indication that a connection over the toll line 220 is to be extended on the automatic basis while the busy signal 322 indicates that the line is engaged. The service observing operator may now connect her set to the toll line but as soon as the dialing begins, relay 323 is operated to disconnect the operator's set in order to in- 110 115 120 125 130

sure against interference on the line during the dialing period. Signal 321 is lighted at this time with a "steady" illumination to indicate the dialing period. It should be remembered that at this time ground from conductor 550 is connected to conductor 551 through the operation of relay 527 and that relay 309 is operated in this circuit. Circuits for signal 321 and relay 323 are, therefore, closed as follows: battery, right hand armature and front contact of relay 309, inner left hand armature and front contact of relay 306, signal 321 to ground and another circuit from battery at relay 309 to the armature and front contact of relay 306, winding of relay 323 to ground at conductor 551.

When the dialing is completed, relay 527 is released and ground on conductor 551 is removed so that relay 309 is released at this time. The circuit for relay 323 is, therefore, broken and the circuit for signal 321 is transferred to the right hand winding of transformer 340. This stage in the progress of the call is, therefore, indicated by the "quiver" indication of signal 321.

In case the trunk lines leading to the wanted subscriber's line are busy or the wanted subscriber's line itself is busy, signal 321 will alternately be flashed from "quiver" to "steady," respectively at the rate of 60 or 120 interruptions per minute, due to the corresponding operations of relay 309. On the other hand, when the wanted subscriber's line has been reached, the illumination of signal 321 will be "steady" and when the called subscriber has answered the call signal 321 will "quiver." At this time, the service observing operator's telephone set is connected to the toll line. In case the called subscriber operates his switchhook to recall the subscriber at 10 or the operator at 100, the signal 321 alternately "quivers" or is made "steady" in phase with the release and operation of relay 309.

When the disconnection takes place at the called subscriber's station, signal 321 will "quiver" and the service observing operator's telephone set is disconnected to insure against interference with the disconnect signal. Thus, it will be seen that a convenient and simple method of indicating and following the progress of an extension of either type of calls over the toll line is available in this service observing equipment.

55 What is claimed is:

1. In a telephone system, the combination of subscriber's stations with a toll line terminating in means for extending the line both manually and automatically to a subscriber's station, a service observing system comprising means responsive during the operation of the said manual extension means to indicate the progress of the manual connection over said line, and means responsive to the operation of the said automatic ex-

10 tension means for indicating in a different manner the progress of the automatic extension over said line.

2. In a telephone system, means for establishing connections on a manual basis, 70 and means for employing alternating currents in establishing connections on an automatic basis, service observing equipment including signaling means to indicate whether a connection is being established on a manual or on an automatic basis and also the progress of a connection being established on the automatic basis.

3. In a telephone exchange system, a line circuit opaque to low frequency currents, 80 means for establishing a connection either on a manual or an automatic basis over said line, a plurality of low frequency current sources, receiving equipments responsive respectively to currents from said sources, a carrier frequency current for rendering said low frequency current effective over said line to control said receiving equipments in automatically establishing a connection.

4. In a telephone exchange system, line 90 circuits opaque to currents of low frequency, a plurality of low frequency current sources, a source of carrier frequency current and means for rendering said currents effective to establish a connection either on a manual 95 or an automatic basis over said line circuits.

5. In a telephone system, line circuits opaque to currents of low frequency, equipment for employing low frequency currents in establishing connections either on a manual or on an automatic basis over said line circuits, and a carrier current at audio frequency for transmitting said low frequency currents over said lines.

6. In a telephone system for handling long 105 distance traffic, lines opaque to low frequency currents, sources of low frequency currents, a source of high frequency current, equipment for rendering said low frequency currents effective in signal control for handling 110 connections on a manual basis over said lines, means for employing said low and said high frequency currents in establishing connections on an automatic basis also over said lines, and means for employing the high frequency current as a carrier agent for the low frequency currents for the signaling relative to said manual connections and also as a carrier agent for the low frequency currents when they are required in said automatic 115 connections.

7. In a telephone system for handling long 125 distance traffic, a line circuit opaque to low frequency currents, sources of low frequency current, a source of audio frequency carrier current for transmitting said low frequency currents over said line, means for employing said carrier frequency alone and also as a carrier for said low frequency currents in controlling respective operations in the auto- 130

- matic establishment of connections in a first direction over said line, and means to render signals effective in the opposite direction over said line circuit during periods signals 5 may be under transmission in the first direction over the same line circuit.
8. In a telephone system for handling connections, a long line circuit substantially opaque to low frequency currents, sources of 10 low frequency current and audio frequency carrier current, means for effecting modulation of the carrier current by the low frequency currents in providing selective signaling currents for use over said line, a 15 receiving system comprising demodulator means including a rectifier, a master relay responsive to the carrier current and relays responsive to demodulated low frequency currents, and means jointly under control 20 of said master relay and said low frequency relays for rendering said signaling currents effective to automatically extend a connection from said line circuit.
9. In a telephone system for establishing 25 connections either on a manual or an automatic basis, a long line substantially opaque to currents at low frequencies, a transmitting system comprising sources of low frequency currents and a source of audio frequency 30 carrier current in which the phenomenon of modulation is established when said low frequency currents may be connected thereto, a receiving system comprising demodulator means, rectifier means and relays respectively 35 responsive to rectified carrier current and to demodulated or low frequency currents, automatic switching means for extending a connection from said line, manual switching means including signals for manually ext- 40 ending connections from said line, and means included with said transmitting system for selectively applying said currents over said line in rendering the receiving equipment effective to establish an automatic 45 connection or to control said signals of the manual switching means.
10. In a system for automatically establishing telephone connections, a line substantially opaque to currents of low frequency, 50 a source of voice frequency alternating current at one end of said line, a source of audio frequency carrier current and a source of low frequency current at the other end of said line, a receiving system comprising rectifier means, demodulator means, and relays 55 respectively responsive to said carrier current and said low frequency current, an automatic switching system under control of said receiving system, means for applying said carrier current to said line in seizing 60 and conditioning said automatic switching system for the reception of selective impulses, means to automatically apply an impulse formed of said carrier current modu- 65 lated by said low frequency current over said

line, and signal means controlled by said impulse to indicate that the switching system is in condition for reception of selective impulses.

11. In a telephone system, a line circuit 70 opaque to direct currents and to low frequency alternating currents, a source of carrier current of audio frequency, a source of low frequency currents for modulating said carrier current, a receiving system for said modulated currents and said carrier current, automatic switching means controlled by said receiving system, and transmitting means for selectively applying said currents over said line to respectively control said automatic equipment in the operations of seizing, dialing and ringing in automatically extending a connection from said line. 75

12. In a telephone system, a calling and a called station, a line circuit opaque to direct current and to alternating currents of low frequency, an automatic switching system including a source of audio frequency current and a low frequency modulating current therefor, means for controlling said switching system from said calling point in connecting said line to said called station, a signal and control means therefor at said calling station, and means responsive on said connection being established to said called station to apply an impulse of said modulated current over said line to energize said signal. 85

13. In a telephone system, a calling and a called station, a line circuit opaque to direct current and to alternating currents of low frequency, a signal and control means therefor at said calling station, an automatic switching system including a source of audio frequency carrier current and a source of low frequency current for modulating said carrier current, means for dialing over said line in controlling said switching system to connect the line to the called station, and means responsive during the operation of said switching system and following establishment of a connection to apply a single impulse of said modulated current over said line at different times in controlling said signal to respectively indicate that dialing 90 may be proceeded with, dialing has been completed, the connection has been established with the called station, the called station has responded and finally that the called station has disconnected. 95

14. In a telephone system, the combination of a toll line with means for extending the line automatically, alternating current sources, means at the originating end of said line for transmitting dialing impulses from an alternating current source for controlling the automatic extension means, means at the terminating end for transmitting to the originating end signaling currents from alternating current sources operating when the 100 105 110 115 120 125 130

path being selected by the automatic extension means is busy, a signal at the originating end, means at the originating end for operating said signal responsive to said 5 signaling currents incoming during the sending of dialing impulses over the toll line.

15. In a telephone system, the combination of a toll line with means for extending the line automatically, alternating current 10 sources, means at the originating end of the line for producing and transmitting dialing impulses from a current source to control the automatic extension means comprising a pulsing circuit, a transformer, means for 15 switching the toll line conductors to the secondary of the transformer and the pulsing circuit through the primary of the transformer when the pulsing device is operated, means at the terminating end for 20 transmitting over the toll line conductors to the originating end signaling current from alternating current sources indicating that the path being selected is busy, a signal at the originating end, and means at the 25 originating end for operating said signal responsive to said signaling currents incoming while the toll line conductors are closed through the secondary of said transformer.

16. In a telephone system, the combination 30 of a toll line with means for extending the line automatically, high frequency and low frequency alternating current sources, means at the originating end of said line for transmitting dialing impulses from an alternating 35 current source for controlling the automatic extension means, means at the terminating end for transmitting to the originating end signals comprising alternating current from a high frequency source modulated by alternating current from a low frequency 40 source operated when the path being selected by the automatic extension means is busy, a signal at the originating end, and means at the originating end for the operation of said 45 signal responsive to the modulated signal incoming during the sending of dialing impulses over the toll line.

17. In a telephone system, the combination 50 of a toll line with means for extending the line automatically, high frequency and low frequency sources, means at the originating end of said line for transmitting dialing impulses for controlling the automatic extension means, an operator's telephone circuit connected to the originating end of the 55 line, means for connecting the dialing means to the originating end of the line and disconnecting the operator's telephone circuit from the line, a visual signal at the originating 60 end, means at the terminating end for trans-

mitting to the originating end signals comprising alternating current from a high frequency source modulated by alternating current from a low frequency source operating when the path being selected by the auto- 65 matic extension means is busy, and means at the originating end responsive to said modulated signals for the operation of said visual signal when the dialing means is operating and for operating the visual signal and for 70 transmitting audible indications to the operator's telephone set when the dialing means is disconnected from the line.

18. A telephone system, including transmission circuits and a source of modulated 75 alternating currents for signaling over said circuits characterized in this that said currents are produced by means comprising a source of direct current, a vibratory relay of the short-circuiting type connected to said 80 source of direct current, said relay provided with an armature having a natural period of high frequency for the production of high frequency alternating current, and a vibratory relay of the same type connected to said 85 direct current source and provided with an armature having a natural period of low frequency for the production of low frequency alternating current, and a transformer 90 having a winding associated with each vibratory relay and a third or output winding for supplying said modulated currents to said transmission circuits.

19. In a telephone system, the combination 95 of subscriber's stations with a toll line terminating in means for extending the line automatically to a subscriber's station, high frequency and low frequency alternating current sources, a supervisory signal at the originating end for indicating the progress 100 of an automatic connection, means at the terminating end for transmitting to the originating end an impulse of current comprising alternating current from a high frequency source modulated by alternating current 105 from a low frequency source at intervals during the operation of the automatic extension means, and means at the originating end responsive to said impulses to actuate said signal on the receipt of the first impulse and to restore said signal to its normal condition upon the receipt of the second impulse and thereafter alternating operating and restoring the signal in response to succeeding impulses.

In witness whereof, I hereunto subscribe my name this 13th day of December, A. D. 1924.

HENRY W. O'NEILL.
